Attorney.

UNITED STATES PATENT OFFICE.

FRANK M. BONHEIM, OF ST. LOUIS, MISSOURI.

ROLLER-SHADE FIXTURE.

Application filed April 10, 1922. Serial No. 551,225.

To all whom it may concern:

Be it known that I, FRANK M. BONHEIM, a citizen of the United States, residing in the city of St. Louis and State of Missouri, have invented certain new and useful Improvements in Roller-Shade Fixtures, of which the following is a specification.

My invention relates to improved shade fixtures, and, is a distinct and practical improvement to overcome certain important and practical objections to, and defects in, shade roller fixtures for windows of the type wherein rollers are adapted to frictionally engage the sides of the window casing to hold the shade, or curtain at a predetermined adjusted position against the pull of the shade-roller.

The object of my present invention is to provide an improved shade fixture for household use which will be simple in construction, neat in appearance, easily and readily actuated and highly efficient for the purpose intended.

A further object of the invention is to provide a roller shade fixture which will not only hold the curtain at any adjusted position, but which will also hold the lower, or stick end of the shade from flopping due to gusts of wind when the window is open, from either the top or bottom.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a front elevation of a portion of a window frame, a shade and a holding device therefor embodying my invention.

Fig. 2, is a plan view showing the holding device in frictional contact with the window frame to hold the shade in any adjusted position against the pull of the shade-roller.

Fig. 3, is a detail showing one of the holding devices disengaged from the window frame.

Fig. 4, is a detail showing the shade holding roller partly in section.

In the illustrative embodiment of my present invention shown in the drawings, the lower fold 1 of the shade, or curtain 2

is provided with a transversely disposed shade stick 3. The upper end of the shade 2 is secured to a suitable constantly acting spring-roller 4 which is mounted at either end by means of suitable shade supporting fixtures 5, which are suitably fixed to the inner opposed faces 6 of the window frame 7.

In carrying out the further aim of my invention, I provide each end of the shade stick 3 with a fixture 8 which is suitably fixed to the shade stick and which is provided with the extended spaced roller supporting arms 9. Eccentrically mounted between the arms 9 of each fixture 8 is a suitable shade holding roller 10 which is mounted upon a shaft 11 surrounded by means of a coiled spring 12 having the extended ends, or arms, designated 13 and 14. Arm 13 of the spring 12 engages a stop 15 upon one of the arms 9 of each fixture 8 and the arm 13 engages a stop 16 carried by one of the side faces of each eccentric roller 10 against which the arm 13 presses to hold the eccentric rollers 10 in their outwardmost position, so as to cause the peripheral face thereof to frictionally engage the inner faces 6 of the window frame 7, thereby holding the roller shade 2 at any adjusted position and prevent flopping of the lower end of shade 2, as is manifest.

Connected to each eccentrically mounted shade holding roller 10, is a suitable cord 17, or its equivalent. These two cords 17 lead inwardly toward each other above the shade-stick to a point approximately midway the ends of the shade stick 3, then they are directed inwardly and downwardly through converging passages 18 in the shade-stick and unite, as at 19, to be continued downwardly in the form of a single shade-cord 20 provided at its lower end with a suitable pull ring 21.

It is evident that when it is desired to adjust the curtain to a new position, or elevation, that the operator merely pulls down on ring 21 which imparts inwardly rotary movement to the eccentric rollers 10 thereby releasing them from peripheral frictional engagement with the inner faces 6 of the window frame 7, and, then the shade 2 may be lowered by pulling down upon ring 21, or the shade may be raised to a new adjusted position by permitting the spring 110 roller 4 to wind the shade 2 thereupon, as is manifest. When the desired adjusted

position is reached in either direction, up or down, pressure is quickly released upon the ring 21, and the coiled springs 12 will quickly rotate the eccentric mounted roller 5 outwardly for peripheral frictional contact with the inner faces 6 of the window frame 7 for holding the shade firmly in the adjusted position.

From the foregoing description, it is evident that I provide a shade fixture which is easily applied to the shade-stick of a curtain shade and which will positively hold the shade in any adjusted position against the spring pull of a shade roller as well as 10 hold the shade from flopping when the shade is down and the windows are open from either above or below.

The many advantages of the herein described invention will readily suggest themselves to those skilled in the art to which it appertains.

I do not desire to be understood as limiting myself to the exact details of construction and arrangement of parts as herein described and illustrated, as it is manifest that variations and modifications may be made without departing from the spirit and scope of my invention and the terms of the following claims, hence I wish it to be understood that I reserve the right to make any such changes, or modifications as may fairly fall within the scope of the appended claims when fairly construed.

What I claim is:

1. In a window shade holding structure, a shade-stick, a bifurcated fixture fixed to each end of the shade-stick and extending beyond the ends thereof, a single eccentrically mounted shade holding roller rotatably supported by the bifurcated end of each fixture, resilient means engaging the roller and said fixture for normally holding the peripheral face of each shade holding roller in frictional contact with the inner face of a window frame to hold the shade-stick in any adjusted position and means for partially rotating the shade holding rollers against the spring action thereof for releasing the shade holding rollers from frictional contact with the inner face of the window frame to permit the raising or lowering of the window shade.

2. In a window shade structure, a shade-stick having converged openings, a bifurcated fixture fixed to each end of the shade-stick and extending beyond the ends thereof, a single eccentrically mounted shade holding roller rotatably supported by the bifurcated end of each fixture, resilient means engaging both the fixture and roller for normally holding the peripheral face of

each shade holding roller in frictional contact with the inner face of a window frame to hold the shade in any adjusted position, and a pull cord connected to the peripheral face of each shade holding roller, the inner ends of said cords passing through the converging openings in the shade-stick and terminating in a single pull-cord which may be actuated for releasing the shade holding rollers from frictional contact with the inner face of the window frame to permit raising or lowering of the window shade.

3. In a window shade structure, a shade-stick having converging openings, a bifurcated holder fixed to and extending from each end of the shade-stick, a stop formed on said holder, a supporting pin carried by each holder, a coiled spring encircling each supporting pin and having one of its ends 75 extended to engage said stop, a shade holding roller eccentrically mounted upon each supporting pin coiled spring, a stop lug fixed to one side of each roller for engagement with the opposite extended end of the coiled spring for normally holding each shade holding roller in outwardly directed frictional contact with the inner faces of a window frame to hold the window shade at any adjusted elevation, a pull cord connected to the peripheral face of each shade holding roller, the inner end of said pull cords passing through the converging openings of the shade-stick and terminating in a single pull cord to be actuated for releasing 90 the shade holding rollers from frictional contact with the inner face of the window frame to permit raising or lowering of the window shade to a new position.

4. In a window shade holding structure, 100 a shade-stick having a pair of converging openings with the upper and lower faces of the shade-stick, a bifurcated fixture fixed to and extending from each end of the shade-stick, a cross pin carried by the bifurcated 105 end of each bifurcated fixture, a coiled spring encircling said pin, a shade holding roller eccentrically and rotatably mounted upon said spring, a lug carried by the bifurcated fixture for engagement with one end 110 of the coiled spring, a lug carried by the roller for engagement with the opposite end of the coiled spring, a bifurcated cord having its outer bifurcated ends connected to the peripheral face of each shade holding 115 roller and having its inner end directed through the converging openings of the shade stick.

In testimony whereof, I have hereunto signed my name to the specification.

FRANK M. BONHEIM.
